CLAIM

The ornamental design for a set of bands for a watch or smart watch, as shown and described.

DESCRIPTION

FIG. 1 is a top side isometric view of our new design for a set of bands for a watch or smart watch.

FIG. 2 is a top side plan is a view of FIG. 1.

FIG. 3 is a bottom side plan view of FIG. 1.

FIG. 4 is a left side elevation view of FIG. 1.

FIG. 5 is a right side elevation view of FIG. 1.

FIG. 6 is a front side elevation view of FIG. 1.

FIG. 7 is a back side elevation view of FIG. 1.

FIG. 8 is an isometric view of the set of bands of FIG. 1 is the worn configuration, it being understood that all other surface are the same.

FIG. 9 is a top side isometric view of our new design for a set of bands for a watch or smart watch, all other surfaces being the same as the embodiment of FIG. 1.

FIG. 10 is a top side plan is a view of FIG. 9.

FIG. 11 is a bottom side plan view of FIG. 9.

FIG. 12 is a left side elevation view of FIG. 9.

FIG. 13 is a right side elevation view of FIG. 9.

FIG. 14 is a front side elevation view of FIG. 9.

FIG. 15 is a back side elevation view of FIG. 9; and,

FIG. 16 is an isometric view of the set of bands of FIG. 1 is the worn configuration, it being understood that all other surface are the same.

The features shown in broken lines in the drawings depict portions of the set of bands for a watch or smart watch that form no part of the claimed design.

1 Claim, 14 Drawing Sheets
